UNITED STATES PATENT OFFICE.

ANTON I. SANDBO, OF ROCK ISLAND, ILLINOIS, ASSIGNOR OF ONE-THIRD TO HENRY W. DAMMANN AND ONE-THIRD TO WILLIAM DAMMANN, BOTH OF ROCK ISLAND, ILLINOIS.

STARTING DEVICE FOR INTERNAL-COMBUSTION ENGINES.

1,229,147.

Specification of Letters Patent.

Patented June 5, 1917.

Application filed March 30, 1916. Serial No. 87,762.

To all whom it may concern:

Be it known that I, ANTON I. SANDBO, a citizen of the United States, residing at Rock Island, in the county of Rock Island and State of Illinois, have invented certain new and useful Improvements in Starting Devices for Internal-Combustion Engines; and I do hereby declare the following to be a full, clear, and exact description of the invention, such as will enable others skilled in the art to which it appertains to make and use the same.

My invention relates to new and useful improvements in starting devices for internal combustion engines and more particularly to that class adapted to be used in connection with automobiles, and my object is to provide a combined gear and belt wheel on the shaft of the motor with which is adapted to coöperate a manually operated gear for rotating the crank shaft.

A further object is to provide means for moving the manually operated gear into mesh with the pulley gear and lock the same in engagement therewith.

A further object is to provide means for rotating the intermeshing gears.

And a further object is to provide means for disconnecting the operating mechanism when a back fire occurs in the motor.

Other objects and advantages will be hereinafter set forth and more particularly pointed out in the accompanying specification.

In the accompanying drawings which are made a part of this application,

Figure 1 is a detail plan view of the forward portion of a vehicle showing my improved device applied thereto.

Fig. 2 is an enlarged detail sectional view of the operating means for the gears.

Fig. 3 is an end elevation of the starting device.

Fig. 4 is an edge elevation of one of the operating dogs, and

Fig. 5 is a perspective view of means for holding the gears in mesh with each other.

Referring to the drawings in which similar reference numerals designate corresponding parts throughout the several views, 1 indicates the chassis or frame of an automobile or similar vehicle and 2 the motor for propelling the same, said frame and motor being constructed in the usual or any pre-

ferred manner, said motor having a crank shaft 3 with which coöperates a hand operated crank 4 for starting the motor.

In order to manually rotate the crank shaft 3 without leaving the seat of the vehicle, I provide in connection with the usual form of fan belt wheel 5, which is universally used upon motor cars, a gear 6, with which meshes a pinion 7 carried by a shaft 8, the inner end of said shaft being rotatably mounted in a bearing 9, of a frame 10, said frame having arms 11 thereon which are pivotally attached to the arms of a bracket 12, said bracket being in turn attached to any suitable part of the motor.

In order to move the pinion 7 into or out of engagement with the gear 6, a rod 13 is extended from the dash 14 of the vehicle to the frame 10, the inner end of the rod being pivotally attached to the frame so that when a lengthwise pull is given the rod the pinion 7 and parts to which it is attached are moved inwardly and upwardly until the pinion is in mesh with the gear 6, and said pinion is held in engagement with the gear by providing a plate 15 on the inner face of the dash, so which plate is provided with inclined faces so that by partially rotating the gripping end 17 of the rod and engaging the same with the highest portion of the inclined faces, the pinion 7 will be held in engagement with the gear until the gripping end is again rotated to the lowermost portion of the plate. Rotating power is applied to the shaft 8 by attaching to the outer end of the shaft a ratchet wheel 18, by means of a key 19, or in any suitable manner, with which coöperates dogs 20 carried by a rotating drum 21, said dogs being pivotally mounted upon one face of the drum by means of screws 22 and when the locking end 23 of the dogs are in engagement with the teeth of the ratchet wheel and the drum is rotated, the shaft 8 will be likewise rotated.

The locking ends 23 are moved into the path of the ratchet wheel by means of springs 24, said springs having one of their ends attached to the dogs, while the opposite ends are attached to the screws, said springs being bent around the screws in such manner as to direct an inward tension on the locking ends of the dogs at all times.

The opposite ends 25 of the dogs 20 are bifurcated to form channels 26 in which are

pivoted the inner ends of the pawls 27, the outer ends of said pawls having a pair of teeth 28 which are adapted to engage with teeth 29 on the inner face of a ring member 30, said ring member being fixed to an arm 31 of the frame 10 by means of bolts 32, or in any preferred manner, said ring member having a hub 33 which surrounds the hub of the ratchet wheel 18 and forms a bearing for the outer end of the shaft 8, the ring member and hub being connected together by means of a spider 34.

The teeth 28 are normally held in engagement with the teeth 29 by means of 15 springs 35, said springs being coiled around the pivot posts 36 and having their ends attached respectively to the dogs 20 and pawls 27, and it will be readily seen that should the crank shaft be given a reverse rotation, 20 as when a back fire occurs in the cylinder, the locking ends of the dogs will be immediately disengaged from the ratchet wheel, in view of the leverage exerted on the bifurcated ends of the dogs when the outer 25 ends of the pawls are caused to swing in the arc of a circle around their pivots by the slight reverse movement of the drum 21, the position of one of the locking dogs when a back fire occurs being shown in dotted lines 30 in Fig 3.

As the outer ends of the pawls 27 move in the arc of a circle around their pivot posts, pins 37 attached to the faces of said pawls are brought into engagement with the inner 35 face 38 of the ring member 30 and, as said face extends inwardly slightly beyond the inner edges of the teeth 29, the teeth 28 will be entirely disengaged from the teeth 29 and held out of engagement therewith until the 40 drum 21 is again rotated to operate the shaft 8. The drum 21 is rotated in one direction by attaching thereto one end of a flexible pull strap 39, said strap member being wrapped any suitable number of times 45 around the drum, whereby, although a drum of small circumference is used, the shaft 8 will be sufficiently rotated to impart one complete revolution to the crank shaft, and in order to place the pull strap in convenient 50 reach of the operator whereby the motor may be started without necessitating the driver leaving his seat, said pull strap is extended through the dash 14 and is provided with a hand hold 40, thus enabling the driver 55 to give an endwise pull to the strap while occupying the seat of the car.

In order to rewind the pull strap 39 upon the drum 21 and position the hand hold adjacent the dash 14, a housing 41 is attached 60 to the frame 10 by means of a screw 42, or in any convenient manner, and in said housing is positioned a flat spiral spring 43, one end of the spring being fixed to the hub 44 of the drum 21, while the opposite end of 65 the spring is fixed in any suitable manner

to the peripheral flange 45 of the housing 41 and when the strap is unwound from the drum, the tension of the spring 43 will be increased to such an extent that when the pull upon the strap is released, the spring 70 will immediately rotate the drum in reverse movement and rewind the strap thereon.

In operation, when it is desired to start the engine, the gripping end 17 of the rod 13 is rotated until said gripping end engages 75 the highest parts of the inclined faces 16, this action swinging the frame 10 rearwardly and upwardly until the pinion 7 meshes with the gear 6 of the belt wheel 5. The hand hold 40 is then grasped and an 80 outward pull given thereto which will result in rotating the drum 21 until the outer ends of the pawls 27 are swung in the arc of a circle around their pivots and moved to the opposite sides of the pivots, thus permitting 85 the locking ends 23 of the dogs to swing into engagement with the teeth of the ratchet 18, and as this operation is almost instantaneous, practically the entire pull upon the strap will be utilized in rotating the shaft 90 8 a sufficient number of times to rotate the crank shaft one complete revolution.

If the motor does not start with the first operation, the pull upon the hand hold is released, whereupon the spring 43 will immediately rewind the strap ready to give another rotation to the shaft 8. Should a premature explosion or back fire occur while an outward pull is being given to the strap, the locking ends of the dogs will be immediately disengaged from the ratchet, through the action of the pawls against the opposite ends thereof, the length of the pawls being greater than the distance between the teeth of the ring member and the ends of 105 the dogs, when said dogs are in their normal engaging positions.

As soon as the engine has started, the gripping end 17 is returned to its initial position, thus permitting the pinion 7 to 110 swing out of engagement with the gear 6, and as the gripping end and hand hold are retained adjacent the face of the dash, they will not interfere in any manner with the 115 operation of the car.

In view of the simplicity of this device, it can be very cheaply constructed and can be readily applied to various forms of motors as the bracket 12 can be easily attached to any suitable part of the motor casing or 120 to the bed plate thereof, the only part required to be changed about the motor construction being that of disconnecting the ordinary belt wheel for the fan and substituting a belt wheel having a gear 6 thereon. 125

It will likewise be seen that in view of the compactness of this device it can be readily positioned within the hood covering the motor without interfering with any 130 part of the motor.

It will likewise be seen that it will require but a minimum amount of exertion to rotate the crank shaft and that said crank shaft can be quickly rotated a number of times if occasion should require.

Having thus fully described my invention what I claim as new and desire to secure by Letters Patent of the United States, is:—

1. The combination with the crank shaft 10 of a motor, of a belt wheel fixed to said motor, a gear fixed to the belt wheel, a pinion swingly mounted adjacent the belt wheel end coöperating with said gear, means to rotate said pinion whereby the crank shaft 15 will be rotated, a rod connected to the pinion mounting to swing said pinion into or out of engagement with said gear, and a cam coöperating with said rod to move and hold the rod in operative position.
2. The combination with a crank shaft and a gear fixed thereto, of a pinion adapted to coöperate with said gear, a shaft carrying said pinion, a support for said shaft, a housing fixed on said support, a hollow 25 drum rotatable on said shaft and disposed over the housing, a coil spring disposed in the housing and connected to the housing and to the said drum, means to manually rotate said drum in one direction, a ratchet 30 fixed to said shaft, dogs mounted on the hollow drum adapted to engage said ratchet and rotate the shaft when the drum is rotated in one direction, and means coöperating with said dogs adapted to disengage the same from the ratchet wheel when reverse rotation is imparted to the crank shaft.
3. The combination with the crank shaft

of a motor, and a gear fixed thereto, of a pinion adapted to intermesh with said gear, a shaft carrying said pinion, means to impart rotating motion to said shaft and pinion whereby the crank shaft will be rotated, a rod to swing said pinion into engagement with the gear, and a cam coöperating with said rod to move the rod and lock the pinion 45 in mesh with said gear.

4. The combination with the crank shaft of a motor and a gear fixed thereto, of a pinion, a shaft to which said pinion is attached, a drum mounted on said shaft, a 50 ratchet wheel fixed to said shaft, dogs pivotally mounted on said drum, one end of the dogs being adapted to engage the ratchet wheel and rotate the same in one direction when the drum is rotated, pawls pivoted to 55 the opposite ends of said dogs, said pawls having teeth at their outer ends, a stationary ring member, teeth on the ring member adapted to be engaged by the teeth of the pawls and cause the pawls to disengage the 60 dogs from the ratchet wheel when reverse rotation is imparted to said crank shaft, and means on the pawls adapted to engage parts of the ring member to release the teeth of the pawls from the teeth of the ring member. 65

In testimony whereof I have signed my name to this specification in the presence of two subscribing witnesses.

ANTON I. SANDBO.
